DOMENICO CARPINELLA AND DOMENICO MUSTO, OF BOSTON, MASSACHUSETTS

IMITATION REED FURNITURE AND FABRIC FOR MAKING THE SAME

Application filed March 10, 1930. Serial No. 434,675.

This invention relates to improvements in the manufacture of furniture of the so-called "reed" type, wherein portions of the furniture are constructed of a fabric composed of woven flexible "reeds" or like strands.

It has long been recognized that the use of genuine reed, rattan, or cane fabric in the construction of furniture presents certain serious objections, the comparatively stiff 10 reeds, rattan strands, or canes often splitting or cracking so as to present projections which may injure the person or catch in the clothing, and the fabric being very stiff and uncomfortable as well as somewhat unsightly 15 because of its necessarily coarse or loosely woven texture. It has been proposed to overcome some of these objects by constructing the fabric of imitation reeds consisting of specially prepared "paper cords", but such 20 imitation reeds lack neatness and extreme durability and the fabric constructed therefrom will not last long or effectively hold the special shapes required in constructing furniture of this type. Another objection of genuine 25 reeds and the like is that they will not effectively absorb and retain surface coatings or finishes, such as stain, paint, varnish and the like.

The primary object of the present invention, therefore, is to provide an improved imitation reed fabric or reed fabric substitute which will have all of the advantages of genuine reed and like fabrics and additional 30 characteristics and advantages by which the objections to the use of genuine reed and like fabrics, in the construction of furniture, are effectively overcome.

A further object is to provide an improved imitation reed fabric and furniture made therewith, whereby the furniture produced will be highly attractive and luxurious in appearance, very comfortable in use, exceedingly sturdy and durable in construction, and light in weight.

Other objects and features of the present invention will become apparent as the nature thereof is better understood, and the same consists in the novel fabric and furniture hereinafter more fully described in connec-

tion with the accompanying drawing, in which:

Figure 1 is a fragmentary view of one of the imitation reed strands used in making the novel and improved fabric forming part of the present invention.

Figure 2 is a fragmentary plan view of the fabric constructed from strands of the kind shown in Figure 1; and

Figure 3 is a perspective view of a chair having portions constructed of the novel fabric shown in Figure 2.

The imitation reed fabric A of the present invention is formed from imitation reeds or cords — 5 — tightly woven in crossed relation, the imitation reeds or cords being pulled taut, the warp cords being spaced, and the woof cords being pressed together in close or contiguous relation during the weaving operation. This provides a durable closely woven fabric which is solid and dainty or luxurious in appearance, particularly in view of the nature of the cords or imitation reeds 5, to be presently described.

Each cord or imitation reed 5 consists of a length of twine formed of several strands 6 of cotton or like fiber tightly twisted or spun together. The term "cotton fiber" is understood to mean cotton or any equivalent fiber of similar essential characteristics, such as cotton twill, mixed cotton and wool fibers or strands, and mixed cotton and silk fibers or strands.

It is especially pointed out that the cords 5 are normally untreated or highly flexible so that they may be readily weaved and textured into the desired shape or design, a decided advantage over the use of genuine reeds, or like rattan or cane strands. More particularly, the present cords or imitation reeds will not split or crack and thereby present stiff or sharp projections likely to cause injury to the person or damage to the clothing. Moreover, the cords or imitation reeds are tightly and uniformly woven so that the resultant fabric is devoid of irregularities and presents a comparatively smooth surface.

The fabric is woven as described above, after which it is stiffened or partly rigidified by impregnating and coating the same with

a hardening and surface forming substance, such as shellac or glue. This renders the fabric quite resilient so that it will yield and yet return to and normally retain its given shape. This impregnation and coating is effected by dipping the fabric in melted glue so that the cords 5 are coated by the glue to be given a smooth hard surface and to be firmly united and held in their closely woven relation. A waterproofing and finishing coating of varnish, stain, or paint may then be applied, if desired. Due to the nature of the cords 5, they readily absorb the glue and finishing coating so as to acquire maximum durability and effectively retain the finishing coating. The latter feature makes it entirely practical to repeatedly clean the fabric by the use of an ordinary cleaning solution.

Merely by way of example, a chair is shown in Figure 3 whose arm rest and back portions are constructed of the fabric embodying the present invention. This figure clearly shows the tight or close weave of the present fabric and illustrates its solid and luxurious appearance. The fabric is of course attached to the chair frame in the usual or any preferred way.

What we claim as new is:

1. An article of furniture comprising a portion constructed of imitation reed fabric, said fabric consisting of warp cords arranged in spaced relation, and a plurality of adjacent woof cords woven over and under the warp cords, the individual cords being substantially the size of ordinary reed strands and each being formed from a plurality of twisted threads.
2. An article of furniture according to claim 1, including a coating on the fabric consisting of a stiffening and surfacing substance for the cords.

In testimony whereof we affix our signatures.

DOMENICO CARPINELLA.
DOMENICO MUSTO.
